(57) **CLAIM**

The ornamental design for a wearable device for emitting light beam to eyebrow, as shown and described.

DESCRIPTION

FIG. 1 is a perspective view of a wearable device for emitting light beam to eyebrow showing my new design; FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top view thereof;

FIG. 8 is a bottom view thereof;

FIG. 9 is an enlarged view thereof, of the portion indicated "9" shown in FIG. 2;

FIG. 10 is an enlarged view thereof, of the portion indicated "10" shown in FIG. 5; and,

FIG. 11 is an enlarged view thereof, of the portion indicated "11" shown in FIG. 8.

In the drawings, the broken lines illustrate enlarged fragmentary view indicators and form no part of the claimed design.
